CONTAINER FOR STEREO TAPE CARTRIDGE

Robert Adell, 1525 Ardmore Drive,
Birmingham, Mich. 48010

Filed June 4, 1968, Ser. No. 12,197

Term of patent 14 years

Int. Cl. D9—99

U.S. Cl. D9—253

FIG. 1 is a top plan view of a container for stereo tape cartridge showing my new design;

FIG. 2 is an end view taken from the right side of FIG. 1;

FIG. 3 is an end view taken from the left side of FIG. 1;

FIG. 4 is a side view taken from the top side of FIG. 1;

FIG. 5 is a side view taken from the bottom side of FIG. 1;

FIG. 6 is a perspective view.

I claim:

The ornamental design for a container for stereo tape cartridge, as shown.
